UNITED STATES PATENT OFFICE.

WILLIAM W. WATSON, OF JAMESTOWN, NEW YORK.

SHEET-METAL WINDOW SCREEN FOR RAILWAY CARS.

Original application filed March 21, 1921, Serial No. 471,465. Divided and this application filed October 19, 1922. Serial No. 595,669.

To all whom it may concern:

Be it known that WILLIAM W. WATSON, a citizen of the United States, residing at Jamestown, in the county of Chautauqua and State of New York, has invented certain new and useful Improvements in Sheet-Metal Window Screens for Railway Cars, of which the following, taken in connection with the accompanying drawings, is a specification.

This application is a division of an application Serial No. 471,465, filed March 21, 1921, and the invention herein set forth relates to sheet metal window screens as adapted for railway cars and similar uses; and more particularly to an improvement upon the car window screen construction shown in Letters Patent Number 1,238,854.

The chief object of this invention is to provide a strong and durable tubular screen frame with locking bolts for the notched guide strips in the frame sides, which bolts are connected so as to be operable to withdraw the same from the lower screen side when in the raised position in the frame of the car above the visible window frame, in which raised position said bolts cannot be manually actuated to withdraw the same by means of the actuating levers, but must be withdrawn by means of a hook.

In the drawings, Fig. 1 is an elevation of a car window with the car frame in section, showing the improved window screen in the elevated position with the hook in position for withdrawing the bolts from their locking engagement with the guide strips on the window frame and drawing down the screen. Fig. 2 is a crosswise sectional view at line 2—2 in Fig. 8; and Fig. 3 is a vertical sectional view at line 3—3 in Fig. 8, the central portions of the frame being broken away to show enlarged sectional views of the frame side. Fig. 4 is a detailed elevation of the central turn or crank plate midway of the upper frame side upon which the slotted ends of the connecting links for the locking bolts are shown; also in dotted line the position of the upper end of the downwardly projecting actuating rod for the bolts; and Fig. 5 is a sectional view of said turn or crank plate, said sectional view being so made as to show two plates in section through the central pivot pin and through each of the connecting pins for said bolt links and actuating rod. Figs. 6 and 7 show lengthwise sectional and end

elevations of the combination corner brace and bolt barrel and pin guideway. Fig. 8 is an elevation of the screen frame, portions of the screen frame being shown in section to show the construction and arrangement of the same as to the lateral frame sides and the central or cross frame strip through which the withdrawing rod passes so that it can be engaged by the withdrawing hook through a slot in the lower frame side. Fig. 9 is a crosswise sectional view of the frame at line 9—9 drawn about double the scale of the frame and guide strips as shown in Fig. 8. Fig. 10 is a sectional view of an upper portion of the frame side showing the central turn or crank plate in section with the slotted links connecting the same with the locking bolts in the withdrawn position. Fig. 11 is a sectional view of the preferred form of one of the bolt barrels showing the spring bolt within the same; and Fig. 12 is an end elevation of the same. Fig. 13 is a perspective view of the insert strip for holding the lateral side springs in working position within the frame side.

Like characters of reference refer to corresponding parts in the several views.

The numeral 15 designates the tubular sheet metal frame side which is cut and bent from the flat sheet metal strip by means of suitable dies so as to form the lengthwise groove 16 along the inner edges of said frame side.

The numeral 17 designates the top rail which is preferably formed of one or more strips of sheet metal shaped so as to provide said lengthwise groove 16 which opens sideways along the inner edge, and the narrow lengthwise groove 18 which also opens sideways along the outer edge, both of said grooves enlarging inwardly. The inner groove 16 enlarges inwardly to receive the spline or holding strip 19 for attaching the screen fabric 20 within the groove 16. The outer groove 18 enlarges inwardly to receive and retain therein the weather striping 21 which fits within the groove 18 and extends beyond the rail or frame side.

The top rail or upper tubular frame side 17 is preferably formed of a plurality of sheet metal strips, the contacting edge portions of which are pressed together and bent into the lengthwise channel grooves 16 and 18 along the inner and outer edges of the same, the edges of said strips being so arranged as to width as to narrow the

mouths of each of said grooves 16 and 18, the thickness of the inturned sheet metal edges so that said grooves may be said to enlarge inwardly to hold the spline 19 and 5 the weather stripping 21. The contacting edges of said sheet metal strips are preferably welded or soldered or otherwise attached so that they cannot turn or move upon one another, thereby giving rigidity 10 to the frame.

The lower cross rail or tubular frame side 22 is preferably made of two sheet metal strips 23 and 24 in somewhat the same form as the upper frame side or cross rail 17, 15 the exception being that the groove 16 is made slightly different, the strip 24 being bent at an inclined angle 25 to prevent the use of the lowering hook 26 upon the screen or frame side in lowering the same, and the 20 lengthwise groove 27 for the guide strip 28 is preferably formed on the outer side of the lower edge of the rail 22 so that said groove 27 opens downward and the guide strip 28 may be pressed downward onto 25 the window sill to make a tight joint between said window sill and the screen frame.

The corners of the screen frame are preferably mitred and united by soldering or 30 welding, though they may be united by any other suitable means. The opposite corners of the upper frame side are provided with the spring bolts 29 and 30 in barrels 31 and 32 which engage in the notches 33 of the 35 guide strips 34 on the window frame at each side.

The opposite lateral edges have the 40 grooves 35 and 36. The groove 35 is formed in a preferably sheet metal channel insert 37 which fits within the groove 38 in the lateral frame side 39. A pair of screws 40 extend through the groove 16 and frame side 39 into the insert 37, suitable threaded nuts 41 being provided in said insert to 45 receive the threaded ends of the screws 40, the spline or holding strip 19 being slotted on its inner or split side, as shown at 42 in Fig. 2, to permit the insertion of the spline 19 in said groove 16. A washer 43 is attached to the screw 40 within the frame side 39 to bear against the inner wall of said frame side and thereby move the insert 37 inward or outward as is desired in order 50 to adjust the screen frame to the opening 55 between the guide strips 34, said opening having as great an amount of variance in different window frames as one-half inch between frames of supposedly the same measurements in different railway cars.

60 The opposite frame side 44 is provided with a channel-shaped insert 45 which carries therein preferably a wooden strip insert 46 having the pairs of notches 47 to receive therein the angularly bent ends of the 65 springs 48. A pair of inwardly projecting

guide pins 49 are provided one in each end of the channel 45, which engages in guideways 50 and 51 in the tubular frame side to thereby hold said insert 45 in perfect alignment as it adjusts outward and inward in 70 moving up and down the guide strips 34, thereby always holding said springs 48 in working position as they press against the inner wall of the lateral frame side 44.

75 It is apparent that this construction of the two frame sides gives adjustable grooves 35 and 36 which are resiliently adjustable for small variances as to the distance between the guide strips 34 by means of the springs 48, and may be permanently adjusted for greater variances by means of the adjusting screws 40 and grooved channel insert 37.

80 The spring bolt 29 has the barrel 31 preferably struck up from sheet metal with the sidewise extension 51 which forms, as stated, a guideway for the guide pin 49 for the insert 45 to hold said insert in proper alignment. Said sidewise extension is preferably oblong instead of round so as to permit the sidewise movement of the pin 49 in its relation to its companion pin 49 at the opposite end of said insert, since absolute accuracy is unnecessary in the movement or placing of these pins as to their vertical adjustment, the necessary part being to hold said pins in vertical alignment, that is, so that the insert 45 does not weave or move sidewise, but the screen frame will travel upward and 90 downward with ease and accuracy.

95 The locking bolts 29 and 30 in their barrels 31 and 32 are connected to a central turn or crank plate 52 by means of links 53 and 54. Said links 53 and 54 are attached to the inner sides of the annular grooved turn or 105 crank plate 52 by means of the wrist pins 55 and 56 in take-up slots 57 and 58 in said links 53 and 54. The slots 57 and 58 permit the use of manually actuatable levers 59 and 60 which are attached to the bolts 29 and 30 110 to manually withdraw the same when the screen frame is accessible as in the lowered position. It is apparent, however, that when in the raised position in the frame 61 of the car side as shown in Fig. 1, said frame being pushed upward between the window sash 62, it is necessary to use the lowering hook 26 to withdraw the bolts 29 and 30 and draw the screen downward into the lowered position as shown in dotted outline in Fig. 1.

115 In order to accomplish this withdrawal of the bolts 29 and 30 when in the raised position, a central tubular cross rail 63 is provided in the screen frame 15, which rail 63 has the attaching grooves 16 along the sides 120 of the same for the screen fabric, thereby providing a hollow tubular way for the rod or lever 64. The rod 64 is pivotally attached to the turn plate 52, preferably as shown in Fig. 5, said rod 64 having an opening in its 125 130

lower end and through which end the lower-
ing hook 26 can be inserted to thereby turn
the turn table 52 by a downward draw and
simultaneously withdraw the bolts 29 and 30
5 and draw downward upon the screen frame,
quickly and easily lowering the same. A
slot 65 is provided central of the lower edge
of the lower screen rail through which the
hook 26 may engage the slotted end of the
10 rod 64.

It is now apparent that the screens may
be pushed upward into the raised position
for protection when in inclement weather,
thereby automatically springing the bolts
15 29 and 30 into the locking notches 33 in the
guide strips 34, and that said screen frame
may be unlocked and withdrawn from said
raised position when it is desired to use the
same by simply pulling downward on the
20 rod 64.

In order to assemble the bolt, turn table
and connective link mechanism with the
manual actuating levers and downward rod
within the top rail 17, a cover 66 is provided
25 for said upper frame side or top rail 17
which fits closely over the same and around
the central cross rail 63 as shown in Figs. 3
and 10, thereby covering the openings 67,
68 and 69 in said top rail 17. The cover 66
30 is channel-shaped and fits closely over said
top rail so it can be sprung onto the same
and give a pleasing finish to said top rail.
Its removal permits immediate access to the
connective joints to assemble the parts in
35 the tubular frame side, or to repair the
same. The right half of this top rail con-
struction is shown in Fig. 10, the left half
being a duplicate in reverse order of the
right half. The cover 66 is shown in Fig.
40 1 with the locking mechanism in dotted out-
line in the top rail beneath the same. Said
cover 66 is not shown in Fig. 8 since said
rail is in section, the side upon which said
cover 66 would be placed being removed.
45 The exact channel shape and the relation of
said cover to the parts is clearly shown in
Fig. 3 in cross section.

The channel strip insert 45 is held against

displacement from the frame side by means
of a screw 70 and a closed end 71 on the 50
lower end of said channel strip 45. The
upper end is held in place by means of a
crosswise pin 72 through the inner end of
the guide pin 49 which does not permit the
escape of said pin 49 from the guide exten- 55
sion 51.

Having thus set forth my invention what
I claim as new and for which I desire the
protection of Letters Patent is—

1. A locking device for a window screen 60
comprising spring actuated locking bolts in
the upper corners of the frame of said
screen, a crank plate in the upper side of
said frame, links connecting said crank
plate with said locking bolts, a tubular cen- 65
tral cross rail in said frame, and a rod ex-
tending from said crank plate down
through said central tubular cross rail and
formed to receive a hook by which said rod
is actuated to move said crank plate and 70
retract said locking bolts.

2. A locking device for a window
screen comprising spring actuated locking
bolts in the upper corners of the screen
frame, tubular barrels for said locking 75
bolts, a crank plate pivotally mounted
within the central portion of the upper side
of the screen frame and connected to said
locking bolts to retract the same when os-
cillated in one direction, a tubular central 80
cross rail in said frame, and a rod attached
to said crank plate and extending through
said tubular central cross rail to retract said
bolts from locking position by a down-
ward pull on said rod. 85

3. A locking device of a window screen
comprising spring actuated locking bolts at
the upper corners of the screen frame, os-
cillatable means in the upper side of the
screen frame for retracting said bolts and 90
means extending across the screen frame
and accessible from the under side of the
screen for actuating said retracting means.

In testimony whereof I have affixed my
signature.

WILLIAM W. WATSON.
